ATTORNEY

UNITED STATES PATENT OFFICE.

FRANK W. BACON, OF LOS ANGELES, CALIFORNIA.

DIRECTORY.

1,418,269.

Specification of Letters Patent. Patented June 6, 1922.

Application filed November 10, 1920. Serial No. 423,093.

To all whom it may concern:

Be it known that I, FRANK W. BACON, a citizen of the United States, and a resident of Los Angeles, in the county of Los Angeles and State of California, have invented certain new and useful Improvements in Directories, of which the following is a specification.

This invention relates to a directory of the 10 type employed for convenient reference when one desires to locate a certain establishment or to obtain other information of various kinds.

An object of the invention is to make provision for indexing the different subjects in such manner that the information can be readily found, even though it should be carried on a page not identified by an index character corresponding with the index letter 20 of the subject under investigation.

The accompanying drawings illustrate the invention:

Figure 1 is a plan view of a directory constructed in accordance with the provisions 25 of this invention, the directory being open to the middle pages;

Figure 2 is a fragmental view of one of the pages of the directory; and

Figure 3 is a fragmental view of another 30 page of the directory.

The directory comprises a series of leaves 1, 2, suitably bound together by fastenings 3. The uppermost leaf 1 is provided along both side margins with suitable index characters 4. The index characters employed, in this instance, are letters of the alphabet. The leaf 1 is ruled longitudinally and cross-wise with lines 5, 6, respectively, to form rectangular spaces, in which spaces may be 40 written the key words or index terms 10 of the subjects on which the information is to be given. For example, in alinement with the index letter "G" is the word "Garages," and opposite the index letter "E" are the 45 words "Electric wiring." Opposite the letter "D" will be found the words "Deer and duck hunting." Also opposite the index letter "D" will be found the word "Detective."

Associated with some of the index terms 50 are sub-index characters 7 whose function will be explained hereinafter.

The leaves 2 are severally indexed, and for this purpose each is provided with a tab 8, the tabs of succeeding leaves being overlapped by those of preceding leaves similar

to the well-known thumb indexes of dictionaries and the like. Each tab 8 carries a different index character 9, which corresponds with the index character 4 in alinement therewith on the leaf 1. For identification purposes the index characters 4, 9, will herein-after be termed "main index characters" to distinguish them from the sub-index characters 7 above referred to. 60

The leaves 2 bear various subjects 11 of information. Now referring more particularly to Figure 2, said figure shows a portion of the leaf 2 bearing the index character "G" and this leaf accordingly bears the 70 names and addresses of individuals or firms operating garages and other business, or any other subject of information, which ordinarily would be listed on the leaf having the index character "G." In compiling the directory, it may be found, as in the instance just mentioned, that a certain page is not entirely taken up by the subjects that would ordinarily be carried on such page. In a directory of this class there would, therefore, 80 be a natural tendency to make it more or less bulky relative to the amount of information contained on the pages, since a large portion of many of the pages would be only partially filled with information. Now referring to the leaf 1, it may be noted that in alinement with the index letter "C" is "Carpet cleaning G." The sub-index character "G," just mentioned, indicates that carpet cleaning establishments will be found indexed, not where they would logically be expected to be listed on the leaf 2 having the index letter "C" thereon, but on the leaf 2 identified by the main index character "G"; and, again referring to Figure 2, we 90 find that the carpet cleaning establishments are listed on the leaf 2 bearing the main index character "G."

As another example of indexing the subjects, it will be noted that "Electric wiring" 100 is listed on the leaf 1 opposite the letter "E," and by referring to Figure 3 it is seen that the electrical contractors are properly listed on the leaf bearing the index character "E." The firms which it may be desired to list on 105 the leaf designated by the letter "E" may only occupy a portion of said leaf, and, consequently, firms which logically would be looked for under other index letters may be found listed on the leaf identified by the 110 index character "E." In order, however, to readily refer to these improperly or non-

alphabetically indexed or listed firms, the sub-index character 7 is employed to make it possible to readily find them. For example, the detective firms are listed under "E," 5 but are referred to on sheet 1 directly opposite the main index character "D," and the sub-index character "E" is placed immediately beneath the word "Detective," so as to direct the attention of the person 10 using the directory to the page bearing the index character "D" and the names and addresses of detective firms.

From the foregoing, it will be clear that space may be economized so that a relatively 15 large amount of information can be carried by a directory of small dimensions, and that the main and sub-index characters make it possible to readily refer to the particular page in the directory bearing the desired information.

I claim:

1. In a directory, the combination of a series of leaves, the uppermost leaf having different marginal index characters and being 25 provided in alinement with said index characters with the corresponding index terms of various subjects of information arranged in successive columns, the other leaves having tabs respectively alined with the index characters and each leaf bearing information corresponding with at least one of the index characters that is alined with its tab.

2. In a directory, the combination of a series of leaves, the uppermost leaf having different marginal index characters and being 35 provided in alinement with said index characters with the corresponding index terms of various subjects of information and 40 having adjacent at least one of the index

terms a sub-index character, the other leaves having tabs respectively alined with the index characters and each bearing information corresponding with the index character that is alined with its tab and at least one of said other leaves bearing information corresponding with the sub-index character on the first-named leaf and not corresponding with the index character with which the tab of said other leaf is alined.

3. In a directory, the combination of a series of leaves, the uppermost leaf having different index characters along both side margins, the other leaves having tabs respectively alined with the index characters 55 and each leaf bearing information corresponding with at least one of the index characters that is alined with its tab, the leaves being bound together along their median line so that when folded along said line the 60 index leaf will occupy a central position in relation with the remaining leaves.

4. In a directory, the combination of a series of leaves, the uppermost leaf having different marginal index characters and being 65 provided in alinement with at least one of said index characters with an index term of a subject of information and having adjacent said term a sub-index character, and one of the other leaves bearing information 70 corresponding with the sub-index character and having its tab alined with the index character with which the sub-index character is alined.

Signed at Los Angeles, California, this 75
4th day of November, 1920.

FRANK W. BACON.
